(57) CLAIM

The ornamental design for an article of footwear as shown and described.

DESCRIPTION

FIG. 1 is a perspective view of a first embodiment of the article of footwear.

FIG. 2 is a front view of the embodiment shown in FIG. 1. FIG. 3 is a rear view of the embodiment shown in FIG. 1. FIG. 4 is a first side view of the embodiment shown in FIG. 1.

FIG. 5 is a second side view of the embodiment shown in FIG. 1.

FIG. 6 is a top view of the embodiment shown in FIG. 1.

FIG. 7 is a bottom view of the embodiment shown in FIG. 1.

FIG. 8 is a perspective view of a second embodiment of the article of footwear.

FIG. 9 is a front view of the embodiment shown in FIG. 8.

FIG. 10 is a rear view of the embodiment shown in FIG. 8.

FIG. 11 is a first side view of the embodiment shown in FIG. 8.

FIG. 12 is a second side view of the embodiment shown in FIG. 8.

FIG. 13 is a top view of the embodiment shown in FIG. 8; and,

FIG. 14 is a bottom view of the embodiment shown in FIG. 8.

The dashed lines present in the drawings within the claimed boundary form portions of the article of footwear and form no part of the claimed design.
